(57) **CLAIM**

The ornamental design for the container for bulk packing of firelogs, as shown and described.

DESCRIPTION

This application is related to U.S. patent application Ser. No. 09/949,179, filed Sep. 7, 2001, entitled, Container for Bulk Packing of Firelogs and Method of Use.

FIG. 1 is a front and side perspective view of a container for bulk packing of firelogs showing my new design;

FIG. 2 is a front elevational view of the container shown in FIG. 1;

FIG. 3 is a side elevational view of the container shown in FIG. 1;

FIG. 4 is a rear elevational view of the container shown in FIG. 1;

FIG. 5 is a top plan view of the container shown in FIG. 1; and,

FIG. 6 is a bottom plan view of the container shown in FIG. 1.
